UNITED STATES PATENT OFFICE.

JAMES W. HAMMETT, OF EUREKA, WEST VIRGINIA.

COMBINED WATER PURIFIER AND ELEVATOR.

SPECIFICATION forming part of Letters Patent No. 635,682, dated October 24, 1899.

Application filed April 11, 1898. Serial No. 677,223. (No model.)

To all whom it may concern:

Be it known that I, JAMES W. HAMMETT, residing at Eureka, in the county of Pleasants and State of West Virginia, have invented a new and Improved Combined Water Purifier and Elevator, of which the following is a specification.

This invention, which relates to power or manually operating water purifying and elevating means, comprehends a novel and simple construction and arrangement of parts which can be readily adjusted to adapt the mechanism for use as an agitating or purifying means or as a water drawer or elevator and which numbers among its characteristic features simplicity of construction, durability, ease of operation, and general effectiveness in use.

My invention embodies a suitable curb or stock frame, a drive-shaft journaled therein, and crank-operated drive-gear for continuously rotating such shaft in one direction, a loop-lift chain supported thereon carrying a bucket at each end, one of which is loaded to overcome the weight of the other, a clutch mechanism for intermittently bringing the chain into a fixed connection with the drive-shaft to be elevated thereby, and an automatically-operated shifting means operated at predetermined intervals by the weighted bucket, whereby during the continuous movement of the drive-shaft in one direction the weighted bucket will be elevated and the lighter bucket lowered by the shaft and such weighted bucket dropped back by gravity to serve as a counterpoise to elevate the other or water-lifting bucket.

Another novel feature of this invention is the peculiar relation of the drive-shaft, the clutch, its tripper devices, and the water-lifting bucket, whereby the several parts can be quickly adjusted to adapt them for use as a water-elevator simply, the loaded bucket then acting as a counterpoise and the raising and lowering of the bucket effected by the crank or other drive-power.

In its subordinate features this invention comprises certain details of construction and peculiar combination of parts, such as will be first described in detail and then specifically pointed out in the appended claims, ref-

erence being had to the accompanying drawings, in which—

Figure 1 is a perspective view of my improvement. Fig. 2 is a vertical section of the same. Fig. 3 is a plan of the drive-shaft, chain-sheave, and the clutch devices. Fig. 4 is a section on the line 4 4 of Fig. 3. Fig. 5 is a detail view of the trip-block. Fig. 6 shows the parts arranged as a water-drawer. Fig. 60 65 7 is a transverse section on the line 7 7 of Fig. 6, the lift-bucket being shown as discharging in the spout, the spout being also shown thrown back in dotted lines. Fig. 8 is a detailed view of one of the buckets.

In its details of construction my invention comprises a curb or stock frame 1, about six feet high and large enough in diameter to accommodate the weight or counterpoise bucket, hereinafter referred to. At the upper end of 70 the curb is journaled a drive-shaft 2, which when the improvement is used solely as a purifier is continuously rotated in the same direction by hand or other draft-power. In the drawings the shaft is shown as having a chain-wheel 3 to receive the drive-chain 4, passed over and driven from the chain-wheel 5^a on the crank-operated shaft 5.

On the shaft 2 is loosely mounted what I term the "lift and supporting sheave" 6, 80 which has a clutch-face 6^a, adapted to be engaged by the sliding clutch 7, having a feather to engage the spline on the drive-shaft and normally held in a clutch engagement with the sheave 6 by a suitable spring 8, it also 85 having an annular grooved boss 9, with which the shifting device engages.

The clutch-shifting device consists of a long longitudinally-reciprocating rod 10, which passes up into the curb, the upper end of 90 which is forked, as at 10^a, and held to slide in the guide-groove 10^b at the upper end of the curb and adapted when elevated to engage the boss 9 and shove the clutch 7 sideways on the shaft 2 out of gear with the sheave 95 6. The lower end of the rod 10 is pivotally joined on the rocker trip-block 12, pivotally and detachably connected to the pendent lug 11 on the bottom of the curb, such block having its opposing ends bifurcated, as at 13 13^a, 100 for the free passage of the ends of the lift-chain 14. The chain 14, which is a loop hung

pendent from the sheave 6, has a bucket at each end, one of such buckets 15 having a solid bottom and perforations 15^a near the bottom for the free ingress and egress of the water. In practice the bucket 15 is partially filled with broken stones for the double purpose of giving it sufficient weight to serve as a counterpoise and to allow the water to break as it passes over the stones, when the bucket 5 sinks and rushes over the top, and also when the bucket is withdrawn, as it empties itself by running out of the perforations 15^a, thereby creating a miniature shower which helps to purify the water. The bucket 15 has a bail 15^b, provided with a central aperture forming a passage for the lower end of the lift-chain, and the bucket is adjustably secured to the same by a split ring 15^c, adapted to engage any one of the links and arranged 10 beneath the bail 15^b to support the same, it being obvious that the surplus end of the chain can hang in the bucket. The bucket 16, which is connected to the other end of the chain, has central discharge-apertures 16^a in 15 its bottom, which open through a valve-seat 16^b, on which is normally held a heavy valve 17, having a central bolt 17^a, which passes down through the bottom of the bucket and has a head 17^b to limit its upward movement, 20 the other end of the bolt being suitably secured to the valve 17 by the nut and washer, as shown. This valve when the parts are arranged as a water-purifying means is held closed by gravity, augmented by the weight 25 of the water within the bucket, and such bucket has its bottom also provided with supplemental openings 17^c for the escape of the water when the mechanism is used as a water-purifying means, such openings 17^c being 30 plugged when the bucket 17 is used as an elevator, as will presently more fully appear.

So far as described it will be readily apparent that when the parts are so set that the bucket rises high enough to engage the 35 trip-block, the clutch-shifter will be moved to disengage the clutch from the sheave 6, which as it is thus released from the shaft freely turns thereon, and in consequence the weight-bucket 15 drops back into the water, 40 and as it thus elevates the other bucket 17 the water in such bucket 17 flows out through the supplemental openings, and as it rises above the water-line in a spray or stream serves to agitate the water and in consequence purifying 45 the same, it being understood the weight-bucket through the medium of its discharging streams on the rise thereof and the influx of water over the stones therein as it sinks also materially aids in agitating and purifying 50 the water. After the sheave 6 has been released, as stated, the bucket 16 is raised until it engages the trip-block, when the clutch device will again be moved to lock the sheave 6 to the shaft, and as it is so adjusted it will 55 again immediately lift the bucket 15, which operation is repeated *ad infinitum*.

To use my improvement as a water drawer or elevator, the trip-block is removed and the shift-rod turned out of engagement with the clutch device and made secure to the curb or 70 removed entirely. The chain is then reciprocated by the alternate operations of the crank-shaft. When thus arranged, the water-bucket 17 (which at this time has its supplemental opening plug) can be raised up through 75 the base portion 1^a of the curb, the spout 18, which normally covers such portion, being tilted back to the position in dotted lines on the drawings, and as it is thus elevated the spout is closed down, and by resting the 80 bucket 17 thereon its valve-head in engaging the spout will move the valve up and uncover the outlets to admit of the discharge of the contents of such bucket. When thus used, the counterpoise-bucket can by shortening the chain be arranged so as to travel within the curb, as illustrated in Fig. 6 of the drawings, sufficiently to permit the bucket 16 to have the necessary vertical movement, and the spout 18 is so constructed that it will not 85 clog up with ice, its pivoted bearings being slotted, as at 18^a, whereby to provide slide-hinged connections, so that the flange 18^b will abut the curb-base member 1^c, and the pivots will drop in the slots below the top of the 90 same in such manner as to support the spout in its tilted position.

To stop the bucket in its proper position as it is elevated, the chain has a ball which engages a projecting portion at the top of the 100 curb.

By arranging the several parts as described and illustrated the same may be used on wells, cisterns, springs, reservoir-tanks, and open ponds.

Having thus described my invention, what I claim, and desire to secure by Letters Patent, is—

1. In a device of the class described; the combination of a vertical curb, a shaft, a 110 chain-sheave mounted on the shaft and having a clutch member, a chain arranged on the sheave and having a bucket at each end, a substantially horizontal trip-block pivotally mounted at the lower end of the curb and 115 having its ends bifurcated to receive the chain, a sliding clutch member mounted on the shaft and adapted to engage the clutch member of said sheave, and a rod arranged within and extending longitudinally of the curb and connected at its ends with the trip-block and the 120 sliding clutch member, and capable of longitudinal reciprocation to shift the latter, substantially as described.

2. In a device of the class described, the 125 combination of a vertical curb, a horizontal supporting-shaft, a chain-sheave mounted on the shaft and having a sliding clutch member, a crank-shaft, sprocket-gearing connecting the shafts, a chain arranged on the sheave 130 and having a bucket at each end, a trip-block pivoted between its ends at the lower end of

- the curb and having bifurcated ends receiving the chain, a sliding clutch member arranged on the supporting-shaft, and a rod arranged within and extending longitudinally 5 of the curb and pivoted at its ends to the trip-block and to the sliding clutch member, said rod being capable of longitudinal reciprocation to shift the clutch member, substantially as described.
- 10 3. In a device of the class described, the combination of a curb having a base member provided with an opening and having vertical slots extending below its upper face, a hinged spout covering the opening and having pivots arranged in the said slots, said spout being provided with a projecting flange adapted to abut against the base member when the spout is raised and the pivots dropped to the bottom of the slots, whereby the spout is re-
- 15 tained in an upright position, substantially 20 as described.
4. In a device of the class described the combination of a curb having a laterally-projecting base member provided with an opening, a spout or cover mounted on the base 25 member, a chain-sheave mounted at the top of the curb, a chain arranged on the sheave with one run in the curb and the other arranged on the exterior of the same and passing through the base member at one side of 30 the spout or cover, buckets arranged on the ends of the chain, and means for operating the latter, substantially as described.

JAMES W. HAMMETT.
